FLUORESCENT LIGHTING FIXTURE

Carl X. Meyer, St. Louis County, and Willard R. Garnett, Bellefontaine Neighbors, Mo., assignors, by mesne assignments, to Emerson Electric Co., a corporation of Missouri

Filed July 11, 1962, Ser. No. 70,881

Term of patent 14 years

(Cl. D48—23)

FIG. 1

FIG. 2

FIG. 3

FIG. 1 is an end elevational view of a fluorescent lighting fixture showing our design;

FIG. 2 is a perspective view thereof as seen from below; and

FIG. 3 is a top perspective view thereof.

The dominant features of our design reside in the portions shown in full lines.

We claim:

The ornamental design for a fluorescent lighting fixture, substantially as shown and described.
